UNITED STATES PATENT OFFICE.

LUTHER G. BRANHAM, OF TULSA, OKLAHOMA.

DESIGN FOR A BOTTLE.

Application filed September 20, 1927. Serial No. 23,472. Term of patent 14 years.

To all whom it may concern:

Be it known that I, LUTHER G. BRANHAM, a citizen of the United States, residing at 701 West Third St., city of Tulsa, in the county of Tulsa and State of Oklahoma, have invented a new, original, and ornamental Design for Bottles, of which the following is a specification, reference being had

to the accompanying drawing, forming part thereof.

The figure is a side view in elevation of a bottle, showing my new design.

I claim:

The ornamental design for a bottle, as shown.

LUTHER G. BRANHAM.
